UNITED STATES PATENT OFFICE.

JOSEPH H. MAGUIRE, OF WAYNE, PENNSYLVANIA.

GAME APPARATUS.

1,369,039.

Specification of Letters Patent. Patented Feb. 22, 1921.

Application filed September 4, 1919, Serial No. 321,678. Renewed July 12, 1920. Serial No. 395,765.

To all whom it may concern:

Be it known that I, JOSEPH H. MAGUIRE, a citizen of the United States, residing at Wayne, in the county of Delaware and State 5 of Pennsylvania, have invented new and useful Improvements in Game Apparatus, of which the following is a specification.

The invention relates to games and toys and has for an object to provide an apparatus 10 for use in or out of doors, for the playing of a game which in many respects simulates the game of golf as it is now generally played in the open.

The invention comprehends among other 15 features the provision of a game apparatus which may be made up in various sizes, to be adapted to the home or amusement parks and the like, and by the use and operation of which, various of the points or playings of 20 the game of golf as now carried on in the open, can be followed out with my game apparatus, to the end that considerable amusement and enthusiasm to persons playing the game particularly those who engage 25 in the game of golf as it is now generally played, will be provided.

In the further disclosure of the invention, reference is to be had to the accompanying drawings constituting a part of this specification, 30 in which similar characters of reference denote corresponding parts in all the views, and in which,

Figure 1—is a plan view of the playing board.

Fig. 2—is a vertical sectional view taken 35 through the playing board showing in detail the understructure.

Fig. 3—is a detail vertical transverse sectional view taken substantially on the line 40 3—3 in Fig. 1, and

Fig. 4—is a vertical transverse sectional view taken through the structure shown in Fig. 3, substantially on the line 4—4 therein.

Referring more particularly to the views, 45 the numeral 10 indicates a playing board and which may be of any desired form and construction and having a portion of its upper surface artistically arranged to simulate the "green" of a golf course, the central 50 portion of the playing board providing an incline 11 which is adapted to constitute a part of the playing surface or "green" of the course, the incline 11 being provided with a series of openings 12 through which a ball 55 13 may pass to drop into a return runway 14 beneath the incline 11 to return the ball

to a transverse groove or pocket 15, common to any or all of the runways 14 that may be provided. The incline 11 at its lower end is also provided with a series of pockets 16 60 which by means of suitable numbers will indicate points in the playing of the game.

On each side of the incline and above the same there is provided a series of alleys 17, the outer ends of which open into a main 65 alley or runway 18, one of the main alleys 18 being provided on each side of the playing board and extending to converge toward the incline near its upper ends and at which point each main alley or runway terminates 70 in a spiral 19 which by the impetus given to the ball and gravity, will bring the ball on to the incline, down which it will gravitate to fall into one of the openings 12 or into one of the pockets 16. Each alley 17 is of a 75 width considerably greater than the diameter of the playing ball as shown, and at its inner end has a ledge 20 provided with a rubber or other holding element 21 for holding the playing ball in position for the 80 drive, this part of the alley being in the nature of a "tee" in the usual game of golf as played. Each alley at its inner end is provided with a driving member 22 which is formed to simulate a golf stick, the handle 85 of which is secured to a block 23 simulating a hand, the latter being suitably pivoted on an upright 24 with a coil spring 25 arranged to swing the free end of the driving member against the ball which is normally held by 90 the element 21 after the driving member has been swung against the movement of the spring 25 so that upon releasing the driving member, the spring will cause the same at 95 its free end to be engaged with the ball and drive it from the so called "tee." This will result in the ball being advanced rapidly along one of the alleys 17 from which the ball will pass into the main alley or runway 18 and thence on to the spiral portion 19 thereof. After passing around the spiral portion 19 the ball will advance to the incline 11 and gravitate down the incline to either fall into one of the openings 12 and thence pass on to the cross alley or pocket 100 15, or missing one of the openings, the ball will be received in one of the many pockets 16.

It will be apparent by reference to Fig. 1, that when a ball or number of balls are 110 received in the cross pocket or groove 15, they can be readily removed therefrom and

- that for this reason the incline 11 does not extend the full length of the playing board but has its lower end terminating a distance from the lower edge of the playing board.
- 5 It will also be apparent by reference to Fig. 2 that the alleys 17 lie in a horizontal plane above the plane of the incline or the pockets 16 or cross pocket 15 and that by having a number of these alleys and an equivalent 10 number of driving elements, the game may be participated in by a number of players at one time.

From the foregoing description it will be apparent that the device described is of a 15 simple construction; consists of few parts that cannot readily get out of order and it will be clear that the device can be constructed in the nature of a home game in small sizes, for disposition in a room in the 20 nature of a pool or billiard table and for use in parks or in other places of out door amusement.

Having described my invention, I claim,

1. A device of the character described 25 comprising a playing board formed to provide a horizontal portion and an inclined portion, alleys in the horizontal portion, a main runway having the alleys communicating therewith and disposed to terminate 30 at the inclined portion, a driving member in each alley for driving a ball therethrough and into the main runway to advance the ball to the inclined portion and pockets for receiving the ball upon gravitation of the 35 latter down said inclined portion.

2. In a device of the character described, the combination with a playing board having a horizontal surface and an apertured inclined portion provided with a series of 40 openings, of alleys in the horizontal por-

tion, main runways having the alleys communicating therewith, said main runways being formed in the horizontal portion and extending to the inclined portion, driving members for the alleys for driving balls 45 through the alleys into the main runways and on to the inclined portion and pockets for receiving said balls upon gravitation of the latter down said inclined portion.

3. A device of the character described 50 comprising a playing board including a horizontal portion and an inclined portion provided with openings, of alleys in the horizontal portion, main runways in the horizontal portion and having the alleys 55 communicating therewith, driving members for driving balls through said alleys into said main runways and on to said inclined portion, pockets adjacent said inclined portion to receive the balls when the latter have 60 gravitated down said inclined portion, a cross pocket and return runways from the openings in the inclined portion to said cross pocket for guiding the balls passing through the openings in the inclined portion 65 into said pocket.

4. In a game apparatus the combination 70 with a playing board and a playing ball, said playing board having a horizontal portion and an inclined portion, of main runways from the horizontal portion to the inclined portion, the former including spirals guiding said ball to the inclined portion, pockets for receiving the balls when the same have gravitated down the inclined 75 portion and means on the playing board for driving said balls on to said runway.

In testimony whereof I affix my signature.

JOSEPH H. MAGUIRE.
